UNITED STATES PATENT OFFICE

2,627,849

GASOLINE HAMMER

Goodwin A. Carlson, Slayton, Minn.

Application January 3, 1950, Serial No. 136,516

5 Claims. (Cl. 123-7)

1

This invention relates to percussive apparatus, such as rock drills, automatic hammers, and like impact-producing mechanisms, and more particularly to such percussive tools wherein the means for imparting impact employs an internal combustion engine.

An object of this invention is to provide means for producing a controlled vertical vibration in the gasoline hammer to enable a tool such as bits, spades, and tampers to properly engage and work on the desired surface.

It has been recognized for a considerable period of time that rock drills and like tools which require compressed air for their motive power are not suitable for prospectors and for use in places where compressed air is not readily available.

It is therefore a further object of the invention to provide a percussive tool which is powered by a prime mover using gasoline as a fuel.

Yet another object of the invention is to provide a percussive apparatus that is sufficiently light in weight for easy transportation from one location to another.

Still further objects reside in the provision of a gasoline hammer that is strong, durable, highly efficient in operation, simple in construction and design, and inexpensive to manufacture.

The invention, briefly described, comprises a housing to which is preferably secured a two-cycle gasoline engine, the said engine driving a drive shaft on which there is secured a first unbalanced flywheel. A second unbalanced flywheel is journaled on the drive shaft. A first bevel gear is secured to the drive shaft and a second bevel gear is secured to the second flywheel. An idler bevel gear engages the first and second bevel gears to impart a rotation to the second flywheel in a direction opposed to the direction of rotation of the first flywheel. This will cause a controlled vertical vibration for the housing. A suitable tool, such as a spade or bit, need but be secured to the housing. The vertical vibration of the gasoline hammer, when held by a resiliently mounted handle, will be such as to provide a reliable and efficient impact or percussive tool.

The aforesaid objects, together with the various ancillary objects of the invention which will become apparent as the following description proceeds, are attained by this gasoline hammer, a preferred embodiment of which has been illustrated in the accompanying drawings, by way of example only, wherein:

Figure 1 is a side elevational view of the gasoline hammer comprising the present invention;

Figure 2 is a front elevational view of the gasoline hammer;

Figure 3 is an enlarged vertical sectional view of the gasoline hammer showing the various parts thereof in greatest detail;

Figure 4 is a horizontal sectional view as taken along line 4-4 in Figure 3;

Figure 5 is a schematic diagram showing the relative motion of the two flywheels which rotate in clockwise and counterclockwise directions respectively; and

2

Figure 6 is a perspective view of the two flywheels.

With continuing reference to the accompanying drawings wherein like reference numerals designate similar parts throughout the various views, reference numeral 10 generally designates the gasoline hammer comprising the present invention. The gasoline hammer 10 comprises a casing 12 to which is bolted or otherwise secured a crankcase 14 on which is mounted a prime mover 16 which preferably comprises a two-cycle gasoline engine. A tool bit 18 is adapted to be secured to the casing 12 by spring clamps 20. The tool bit 18 may be a spade, bit, tamper or the like, and such are readily available commercially for use in other gasoline or compressed air percussive tools.

As shown in Figure 3, the casing 12 is formed with an upwardly extending, externally threaded hollow cylindrical projection 22 on which is threadingly engaged a collar 24. Within the cylindrical projection 22 is formed an additional cylindrical projection 26. Slidably embracing the collar 24 is a tubular portion 28 of a handle 30 which has a downwardly extending shaft 32 slidably positioned through collar 24. An annular flange 34 is formed on the shaft 32 and a piston pin 36 is engageable within cylindrical projection 26. A spring 38 is provided to bias the flange 34 and the collar 24 while spring 40 biases the housing 12 and the collar 34. Thus, there is provided a handle resiliently mounted on the housing 12. Secured to the casing 12 and resiliently supported thereon is a fuel tank 42 which is held to the casing 12 by brackets 44. The fuel tank 42 is cushioned by resilient mat 46.

The piston 48 of the prime mover 16 drives a piston rod 50 which is connected to a crank shaft 52 which, in turn, drives the drive shaft 54 of the gasoline hammer. A crankcase cover is bolted to the crankcase 14 and is generally indicated by reference numeral 56. In this manner, the connection between the piston rod 50 and the crank pin 58 and the crank rod 52 may be readily inspected and repaired if necessary.

Pinned to the drive shaft 54 is a first unbalanced flywheel 60. The flywheel 60 is provided with an eccentrically mounted weight 62. A second flywheel 64 freely rotatable about the shaft 54 is provided with an eccentrically mounted weight 66 to unbalance the flywheel 64.

Rigidly secured to the shaft 54 is a first bevel gear 68. A second bevel gear 70 is secured to the flywheel 64 and is rotatable about the shaft 54. An idler bevel gear 72 engages the bevel gears 68 and 70 in order to rotate the flywheel 64 in a direction opposed to the direction of rotation of the shaft 54.

As shown best in Figure 5, the unbalanced flywheels 60 and 64 have been schematically illustrated at the different stages of each revolution of the shaft 54. In position "A," the flywheels are shown with the weights 62 and 66 at the top, resulting in unbalance. As shown in "B," the weights 62 and 66 balance each other to provide

horizontal balance; as shown in "C," the flywheels are again in vertical unbalance with the weights 62 and 66 at the bottom of the rotation. At position "D," the wheels are again in balance with the weight 62 balancing the weight 66. Accordingly, the effect of the flywheel rotation will be a minimum horizontal vibration and a maximum controlled vertical vibration parallel to the longitudinal or vertical axis of the machine and transmitted through the device to the surface engaged by the bit for drilling or digging thereof. The shaft 54 extends without the housing 12 and is journaled in the housing by suitable roller or ball bearings 74. Rigidly attached to the outermost end of the shaft 54 is a pulley wheel 76 which is readily engaged by a rope for starting the gasoline hammer. By rotating the pulley wheel 76, the bevel gear 68 is rotated, thus imparting rotation upon the idler gear 72. Rotating with the idler gear 72 is a shaft 78 which is connected to a magneto 80 of conventional design. The magneto 80 is connected to the sparkplug 82 or sparkplugs, depending upon the size of the engine 16. In this manner, by rotation of the pulley wheel 76, the shaft 78 actuates a magneto 80 to provide starting current through the sparkplug 82 to start the prime mover 16.

Since from the foregoing, the construction and advantages of this gasoline hammer are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents of this gasoline hammer may be resorted to which fall within the scope of the appended claims.

Having described the invention, what is claimed as new is:

1. A gasoline hammer comprising a housing having a drive shaft rotatably journaled therein, a reciprocating type prime mover operatively connected to said drive shaft for effecting rotation of said shaft, a first unbalanced flywheel rigidly secured to said shaft, a second unbalanced flywheel rotatably secured on said shaft, means secured to said shaft and said second flywheel selectively rotating said second flywheel in an opposite direction to the normal rotation of said first flywheel, said housing adapted to have a tool secured thereto and extending downwardly therefrom.

2. In a gasoline hammer, the combination with a reciprocating type prime mover of means to impart a controlled vertical vibration to said gasoline hammer, said means comprising a drive shaft, connecting and crank rods interconnecting said reciprocating type prime mover with said drive shaft for effecting rotation thereof, a first unbalanced flywheel rigidly secured to said shaft, a second unbalanced flywheel rotatably secured on said shaft and means secured to said shaft and said second flywheel selectively rotating said second flywheel in an opposite direction to the normal rotation of said first flywheel.

3. In a gasoline hammer, an internal combustion engine having a reciprocating piston, means imparting a controlled vertical vibration to said gasoline hammer, said means comprising a drive shaft, connecting and crank rods interconnecting said piston and drive shaft for effecting rota-

tion thereof, a first unbalanced flywheel rigidly secured to said shaft, a second unbalanced flywheel rotatably secured on said shaft, and means selectively rotating said second flywheel in an opposite direction to the normal rotation of said first flywheel and said shaft, said last recited means comprising a first bevel gear secured to said shaft, a second bevel gear secured to said second flywheel, and an idler bevel gear engaging said first and second bevel gears.

4. A gasoline hammer comprising a housing having an internal combustion engine and drive shaft supported thereby, said internal combustion engine having a reciprocating piston disposed on a vertical axis, and said drive shaft being rotatably journaled in said housing and lying along an axis perpendicular to said vertical axis, connecting and crank rods, interconnecting said piston and drive shaft for effecting rotation thereof, and means mounted on said drive shaft for imparting a controlled vertical vibration in supplement to the vibration effected by said reciprocating piston, said last-named means including a first unbalanced flywheel rigidly secured to said shaft for rotation therewith, a second unbalanced flywheel rotatably secured on said shaft, means secured to said shaft and connected to said second flywheel for selectively rotating said second flywheel in a direction opposite to the direction of rotation of said first flywheel.

5. A gasoline hammer comprising a housing having an internal combustion engine and drive shaft supported thereby, said internal combustion engine having a reciprocating piston disposed on a vertical axis, and said drive shaft being rotatably journaled in said housing and lying along an axis perpendicular to said vertical axis, connecting and crank rods interconnecting said piston and drive shaft for effecting rotation thereof, and means mounted on said drive shaft for imparting a controlled vertical vibration in supplement to the vibration effected by said reciprocating piston, said last-named means including a first unbalanced flywheel rigidly secured to said shaft for rotation therewith, a second unbalanced flywheel rotatably secured on said shaft, means secured to said shaft and connected to said second flywheel for selectively rotating said second flywheel in a direction opposite to the direction of rotation of said first flywheel, and said last included means comprising a first bevel gear secured to said shaft, a second bevel gear secured to said second flywheel, and an idler bevel gear engaging said first and second bevel gears for effecting relative rotation.
